UNITED STATES PATENT OFFICE.

MICHEL HENRY MARIE JOSEPH WIBAULT, OF BILLANCOURT, FRANCE, ASSIGNOR TO SOCIÉTÉ ANONYME DES AVIONS MICHEL WIBAULT, OF BILLANCOURT, SEINE, FRANCE, A CORPORATION OF FRANCE.

METALLIC CONSTRUCTION OF SURFACES OR PARTS OF AEROPLANES OR THE LIKE.

Application filed September 8, 1924, Serial No. 736,625, and in France September 10, 1923.

The present invention relates to a method of metallic construction of surfaces or parts of aeroplanes or the like, comprising a metallic girder like structure, constituted by 5 spars, ribs or the like, upon which is secured a likewise metallic covering.

Methods of construction of surfaces of this kind are already known, in which the covering sheets are interrupted at each rib 10 and are provided at this position with a flange, either integral with the covering sheet or secured thereto, the terminal flanges of the sheets being secured to the ribs, with or without a cover for the joint, by riveting 15 or in any suitable manner.

The construction in accordance with the present invention is characterized by the fact that the covering sheet, which is continuous for an area extending over several 20 ribs, comprises at the position of each rib, a pressed up fold, that is to say a fold standing up perpendicularly and externally to the surface of the covering sheet and adapted to cap the rib which is left plane.

25 The accompanying drawings represent merely by way of examples several forms of carrying out this method of construction.

Figure 1 is a view in vertical section of a 30 surface-element, showing the connection of two covering sheets to the girder elements by pressed folds.

Figures 2 and 3 are corresponding partial views of modifications.

Figure 4 is an end view of a thick surface such as a wing of an aeroplane.

Fig. 5 is a view, corresponding to that of Figs. 1, 2 and 3 of another modification.

In the example represented in Figure 1, the surface-element is composed of an upper covering *e* and a lower covering *d* each comprising at suitable distances apart, parts *e*¹ and *d*¹ respectively, folded at right angles to their surfaces and lying parallel to the direction of flight of the aeroplane. In 45 these folds are engaged the extremities of ribs *c* made of flat sheet; the connection of the coverings *e* *d* with these ribs *c* is effected by riveting through the pressed folds *e*¹ *d*¹ and the extremities of the ribs *c* at *e*² *d*².

50 The ribs, instead of being continuous as shown in Figure 1, may be discontinuous (see Figures 2 and 3); the elements *c* *c* of the ribs, connected to the upper and lower

coverings *e* and *d*, may be identical, as in Figure 2 or different, as represented in 55 Figure 3, in which latter the rib element *c* gripped by the pressed fold *e*¹ of the upper covering *e* has the cross-section of an inverted T, while the rib element *c* connected to the lower covering *d* is constituted by an angle section.

Figure 4 represents in profile or end view, a thick surface such as a wing of an aeroplane or the like, constituted in the manner indicated in Figure 1, with apertured ribs 65 *c* connected to the external folds *e*¹ and *d*¹ of the upper and lower coverings *e* and *d*.

As shown in Fig. 5, the sheet of the upper covering *e* may be secured to the ribs *c* by means of pressed folds *e*¹, and of rivets *e*², 70 while the sheet of the lower covering *d*, left plane, bears at the position of each rib *c*, against a turned-over edge *c*¹ of this rib, to which the lower covering sheet is secured by riveting at *c*².

The assembling is effected very simply: the ribs *c* are first of all secured to the lower covering, and the upper covering is then mounted in the manner of a lid used to close a box.

75 This method of construction presents the following advantages:

(1) The covering sheets being continuous, even to the point of connection with the elements of the girder (Figure 1), the staunchness of the surface is ensured.

(2) The pressed folds in the upper covering sheet and the turned-over edges of the lower part of the ribs, make the latter very rigid, which obviates distortion; it also affords without any external bracing, a wing having a permanent shape which is retained indefinitely in service. Moreover the wing thus constituted possesses considerable strength to resist torsion.

80 Having thus described my invention what I claim is:—

1. In wings and the like members constructed of sheet metal for aeroplane flying machine and other aircraft, the combination with separate metal ribs, of an external sheet metal covering, and metallic means for rigidly securing said covering to said ribs, said covering being continuous over a plurality of said ribs and having integrally formed pressed up folds, extending perpen-

- 5 dicularly external to the covering surface, said folds being parallel to and capping the edges of the ribs over which the covering extends, said ribs being arranged substantially perpendicular to the sheet metal covering.
- 10 2. In wings and the like members constructed of sheet metal for aeroplane flying machine and other aircraft, the combination with separate metal ribs, of an external sheet metal covering, and rivet means rigidly securing said covering to said ribs, both heads of said rivets appearing upon the external face of the covering, said covering being continuous over a plurality of said ribs and having integrally formed pressed up folds extending perpendicularly external to the covering surface, said folds being parallel to and capping the edges of the ribs over
- 15 20 which the covering extends, said ribs being arranged substantially perpendicular to the sheet metal covering.
3. In wings and the like members constructed of sheet metal for aeroplane flying machines and other aircraft, the combination with the metal ribs, of an upper external sheet metal covering continuous over a plurality of said ribs and secured to said ribs by means of pressed up folds external to the covering surface, parallel to and capping the upper edges of the ribs over which the covering extends, and a plane lower external sheet metal covering continuous over a plurality of ribs, and secured to the lower edges of said ribs by means of a flange formed in the lower edges of the ribs.

25 30 In testimony whereof I have signed my name to this specification.

MICHEL HENRY MARIE JOSEPH WIBAULT.
